UNITED STATES PATENT OFFICE.

JAMES K. DIAMOND, OF GRAND RAPIDS, MICHIGAN, ASSIGNOR TO CLIPPER BELT LACER COMPANY, OF GRAND RAPIDS, MICHIGAN, A CORPORATION OF MICHIGAN.

TOOL FOR CLENCHING BELT-FASTENERS.

1,128,421.

Specification of Letters Patent. Patented Feb. 16, 1915.

Application filed January 29, 1914. Serial No. 815,149.

To all whom it may concern:

Be it known that I, JAMES K. DIAMOND, a citizen of the United States of America, residing at Grand Rapids, in the county of Kent and State of Michigan, have invented certain new and useful Improvements in Tools for Clenching Belt-Fasteners; and I do hereby declare the following to be a full clear, and exact description of the invention, such as will enable others skilled in the art to which it appertains to make and use the same.

This invention relates to improvements in tools for clenching belt fasteners, and more particularly to means for alining the fasteners in such devices as described in my Patent No. 1,060,746 issued May 6, 1913, and its object is to provide in a tool of this class means for holding the fasteners which will be simple and effective in operation, and to provide the device with various novel features of construction and operation as hereinafter more fully described and particularly pointed out in the claims, reference being had to the accompanying drawings, in which:

Figure 1 is a plan view of a device embodying this invention with parts broken away; Fig. 2 is a transverse sectional elevation of the same on the line 2—2 of Fig. 1; Fig. 3 is a fragmentary section, on the line 3—3 of Fig. 1; Fig. 4 shows the device in transverse section placed between the jaws of a vise in position to operate upon the fasteners; and Fig. 5 shows the device closed by the vise and the fasteners clenched upon the belt.

Like numbers refer to like parts in all of the figures.

The device comprises a base 1, the upper surface of which forms one of the clenching dies, the said base member being provided with a groove or rabbet extending longitudinally of its rear edge, in which a receiving member 2 is slidably mounted. Guide pins 3 extend through the said receiving member and are supported at their respective ends by the base 1 and a plate 4 secured to the rear edge of said base, and springs 5 surrounding said pins 3 yieldably force the said member toward the forward edge of the base.

The receiving member 2 projects above the surface of the base 1 and is provided in

its forward edge with a series of transverse grooves 6 at regular intervals to receive the middle curved portion of the respective belt fasteners. A vertically slideable retaining bar 7 is located near the forward edge of the base 1 and is normally raised to project above the surface of the base by springs 8, but may be depressed under pressure to recede flush with the said face. This bar 7 is provided in its side opposite the receiving member 2 with a series of recesses 7^a corresponding to the recesses 6 in the said member, these recesses being preferably alternately deep and shallow to receive the alternately arranged ends of the belt fasteners which have legs of unequal length.

The device is provided with an alining member 9 mounted on the receiving member 2 and provided with a series of projections to enter the grooves in the said receiving member to engage the fasteners therein and the said alining member is retained on the receiving member by screws 10 which pass therethrough and is yieldably pressed downward by springs 11 beneath the heads of said screws.

A releasing screw 12 has a bearing in the plate 4 at the back of the base, is screwed into the body of the receiving member 2 and provided with a knurled head by which it may be manually turned to draw the said receiving member away from the bar 7, compressing the springs 5.

The pivoted clenching die 13 is provided on its respective ends with arms 14 which embrace the respective ends of the receiving member 2 and are slotted at right angles to the clenching face of the die, and pivot screws 15 extend through said slots and pivotally connect the said die to the receiving member. The die and base are provided on their outer surfaces with shoulders 16 adapted to engage the corners of the jaws 17 of an ordinary vise to support the tool therebetween when partially opened as illustrated in Fig. 4.

In operating this device, the pivoted die 13 is raised and the receiving member 2 is retracted from the retaining bar 7 by the screw 12, which gives sufficient clearance for the easy insertion of the belt fasteners 18 into the recesses 6 of the receiving member 2, and the corresponding recesses 7^a in the retaining block 7. After the fasteners 18

have been properly arranged in the device as shown in Fig. 2 the screw 12 is turned to allow the receiving member 2 to move forward under tension of the springs 5 until 5 stopped by engagement of the bottoms of the recesses 6 by the curved portions of the fasteners. During this movement the projections on the alining member 9 have engaged the fasteners 18 and pressed them 10 firmly against the clenching surface of the base and retained them in this position under tension of the springs 11. The pivoted die 13 is now moved downward until its clenching surface engages the upper legs of 15 the fasteners 18, and the device is then placed between the jaws 17 of an ordinary machinist's vise being supported by the shoulders 16, as illustrated in Fig. 4. The end of the belt 19 may now readily be placed 20 between the open ends of the fasteners 18 and adjusted to the proper depth by engagement with the receiving member 2, and as the jaws 17 are forced together the pivoted die 13 will be moved toward the base 1, 25 clenching the fasteners 18 upon the belt in proper alinement. The die 13 by virtue of its slotted connection with the receiving member 2 is adapted to move bodily toward or from the base 1 and hence automatically 30 adjust itself to different thicknesses of belts and the retaining bar 7 when engaged by the belt will yield sufficiently to permit the fasteners 18 to be properly clenched. The device is shown at the completion of the operation in Fig. 5.

What I claim is:—

1. A tool for clenching belt fasteners, comprising a base, a receiver on the base and having a series of grooves to receive the 40 curved portions of belt fasteners, and a bar spaced apart from the receiver and having recesses opposite the said grooves to receive the inturned ends of the fasteners.

2. A tool for clenching belt fasteners, comprising a base, a receiver on the base having grooves to receive the curved middle portions of belt fasteners, a bar slidale in the base and having recesses opposite the said grooves to receive the ends of the fasteners, and a yieldable support for the bar.

3. A tool for clenching belt fasteners, comprising a base, a receiver slidale on the base and having grooves to receive the middle of belt fasteners, a bar slidale in the base and having recesses opposite the said slots, and means for yieldably moving the receiver and bar.

4. A tool for clenching belt fasteners, comprising a base, a receiver projecting above the base and having grooves to receive the middle portions of belt fasteners, a bar yieldably mounted on the receiver and having projections extending within said grooves, a bar slidale in the base and having recesses opposite the grooves to receive

the ends of fasteners, and means for yieldably supporting said slidale bar.

5. A tool for clenching belt fasteners, comprising a base, a receiving member slidale on the base and having a series of grooves to receive the curved portions of belt fasteners, a retaining bar opposite the receiving member to engage the ends of the fasteners, and means for moving said receiving member toward or away from said bar.

6. A tool for clenching belt fasteners, comprising a base, a receiving member slidale on the base and having a series of grooves to admit the middle of the fasteners, a retaining bar opposite the receiving member to oppositely engage one end of the fasteners, means for moving said receiving member toward or away from said bar, and a pivoted die to engage the fasteners opposite the base.

7. A tool for clenching belt fasteners, comprising a base, a receiving member slidale on the base and having a series of grooves to receive the middle portions of the fasteners, a retaining bar in the base opposite the receiving member to engage the belt fasteners, said bar being yieldably raised above the clenching surface of the base and adapted to be depressed flush with the same, and means for moving the receiving member toward or away from said bar.

8. A tool for clenching belt fasteners, comprising a base, a receiving member slidale on the base and having grooves to receive the middle of the fasteners, a retaining bar on the base opposite the receiving member to engage the ends of said fasteners, a spring to yieldably force the receiving member toward the retaining bar, and means for moving said member in the opposite direction.

9. A tool for clenching belt fasteners, comprising a base, a receiving member transversely slidale on the base and having recesses to receive the middle of the fasteners, a retaining bar opposite the receiving member to engage one end of said fasteners, a spring to yieldably force the receiving member toward the retaining bar, and a screw in the receiving member whereby the same may be moved away from the retaining bar.

10. A tool for clenching belt fasteners, comprising a base, a receiving member slidale on the base and having grooves to receive the middle of said fasteners, a retaining bar on the base opposite the receiving member to engage the ends of said fasteners, said bar being yieldably raised above the face of the base and adapted to be depressed flush with the same, springs to force the receiving member toward said bar, and means for moving said member away from the bar.

11. A tool for clenching belt fasteners,

- comprising a base, a receiving member slideable on the base and having grooves to receive the fasteners, an alining member having portions extending into said grooves in the receiving member, and springs adapted to yieldably engage the receiving member with the fasteners, a retaining bar on the base opposite the receiving member to engage the ends of said fasteners, and means for moving said receiving member toward or away from said bar. 5
12. A tool for clenching belt fasteners, comprising a base, a receiving member slideable on the base and having recesses to receive the curved middle of belt fasteners, an alining member composed of a bar yieldably mounted on said receiving member and having projections entering said grooves to engage fasteners therein, a retaining bar on the base opposite the receiving member to engage one of the ends of each of said fasteners, and means for moving the receiving member toward or away from said retaining bar. 15
13. A tool for clenching belt fasteners, comprising a base, a receiving member slideable on the base and having grooves to receive the middle portions of belt fasteners, an alining member comprising a bar yieldably mounted on the said member and having projections to enter said grooves and engage the fasteners therein, a retaining bar on the base opposite the receiving member to engage the ends of said fasteners, and means for moving said receiving member toward or away from said bar. 20
14. A tool for clenching belt fasteners, comprising a base, a receiving member slideable on the base and having grooves to receive the middle portions of the fasteners, a retaining bar on the base opposite the receiving member and having corresponding opposing recesses, said bar also being yieldably supported above the surface of the base and adapted to be depressed flush therewith, springs to normally force the receiving member toward the retaining bar, means for moving said member away from said bar, and an alining member consisting of a bar yieldably mounted on the receiving member and having projections to enter the said grooves and engage the fasteners therein. 25
15. A tool for clenching belt fasteners, comprising a base, a receiving member slideable on the base and having grooves to receive the middle portions of belt fasteners, an alining member comprising a bar yieldably mounted on the said member and having projections to enter said grooves and engage the fasteners therein, a retaining bar on the base opposite the receiving member to engage the ends of said fasteners, and means for moving said receiving member toward or away from said bar. 30
16. A tool for clenching belt fasteners, comprising a base, a receiving member slideable on the base and having grooves to receive the fasteners, an alining member having portions extending into said grooves in the receiving member, and springs adapted to yieldably engage the receiving member with the fasteners, a retaining bar on the base opposite the receiving member to engage the ends of said fasteners, and means for moving said receiving member toward or away from said bar. 35
17. A tool for clenching belt fasteners, comprising a base, a receiving member slideable on the base and having grooves to receive the middle portions of belt fasteners, an alining member composed of a bar yieldably mounted on said receiving member and having projections entering said grooves to engage fasteners therein, a retaining bar on the base opposite the receiving member to engage one of the ends of each of said fasteners, and means for moving the receiving member toward or away from said retaining bar. 40
18. A tool for clenching belt fasteners, comprising a base, a receiving member slideable on the base and having grooves to receive the middle portions of the fasteners, a retaining bar on the base opposite the receiving member and having corresponding opposing recesses, said bar also being yieldably supported above the surface of the base and adapted to be depressed flush therewith, springs to normally force the receiving member toward the retaining bar, means for moving said member away from said bar, and an alining member consisting of a bar yieldably mounted on the receiving member and having projections to enter the said grooves and engage the fasteners therein. 45
19. A tool for clenching belt fasteners, comprising a base, a receiving member slideable on the base and having grooves to receive the middle portions of belt fasteners, an alining member comprising a bar yieldably mounted on the said member and having projections to enter said grooves and engage the fasteners therein, a retaining bar on the base opposite the receiving member to engage the ends of said fasteners, and means for moving said receiving member toward or away from said bar. 50
20. A tool for clenching belt fasteners, comprising a base, a receiving member slideable on the base and having grooves to receive the middle portions of belt fasteners, an alining member comprising a bar yieldably mounted on the said member and having projections to enter said grooves and engage the fasteners therein, a retaining bar on the base opposite the receiving member to engage the ends of said fasteners, and means for moving said receiving member toward or away from said bar. 55

engage the fasteners therein, a retaining bar on the base opposite said receiving member having recesses corresponding to those in the said member yieldably supported above the surface of the base and adapted to be depressed flush with the same, and means for moving said receiving member toward or from the retaining bar.

21. A tool for clenching belt fasteners, comprising a base, a receiving member slideable on the base and having grooves to receive the middle portions of the fasteners, a retaining bar on the base opposite the receiving member and having corresponding opposing recesses, said bar also being yieldably supported above the surface of the base and adapted to be depressed flush therewith, springs to normally force the receiving member toward the retaining bar, means for moving said member away from said bar, and an alining member consisting of a bar yieldably mounted on the receiving member and having projections to enter the said grooves and engage the fasteners therein. 60

In testimony whereof I affix my signature in presence of two witnesses.

JAMES K. DIAMOND.
